UNITED STATES PATENT OFFICE

GEORGE H. JENTZEN, OF JERSEY CITY, NEW JERSEY

CLOTHESPIN

Application filed August 16, 1927. Serial No. 213,288.

This invention relates to improvements in clothes pins, and has for its object to provide a clothes pin having a split with a series of spaced apart enlargements of varying sizes in order to clamp material of various thicknesses more securely upon a clothes line.

Another object of the invention is to provide a clothes pin having a split to receive a clothes line the terminal of said split being enlarged by a bone to do away with the usual V-terminal which has a tendency to splitting at that part.

A further object of the invention is to provide a wooden clothes pin so formed as to prevent splitting under ordinary usage.

With the above and such other objects in view as may hereinafter more fully appear, I have invented the clothes pin illustrated in the accompanying drawings, in which:

20 Figure 1 is a plan view of a clothes pin made according to my invention;

Figure 2 is a section on line 2—2 of Figure 1;

Figure 3 is a view similar to Figure 1 showing a modification;

Figure 4 is a similar view of another modification;

Fig. 5 is a plan view of another modification of the invention;

30 Fig. 6 is a plan view of another modification of the invention;

Fig. 7 is a plan view of another modification of the invention;

Fig. 8 is a plan view of a still further modification of the invention; and

Fig. 9 is a side elevational view partly in section taken through the longitudinal axis of Fig. 8.

Like reference characters indicate like parts throughout the following specification and in the several views in the drawings, in which 1 indicates a clothes pin the body 2 of which is relatively thick with flattened sides 3 and 4 throughout a portion of the length, said body having the usual bifurcated portion 5 the split 6 of which is tapering and terminates in a bore 7 having the double function of forming a line receiving enlargement and a split preventing terminal so formed that strain of spreading the legs 8

and 9 is distributed over a considerably enlarged area. Spaced at suitable intervals apart from the first bore 7 are cut outs 10 and 11 graduating in size from the said bore 7 the latter cut outs being intended to receive the line and goods hung thereon, the purpose of the graduated enlargement also being to receive lines of various diameters as well as goods of different thicknesses. The side walls are reduced in thickness at the points 3 and 4 where there is the least strain, whereby additional resilience is provided for said legs 8 and 9.

The cut outs 14 of Fig. 3 are triangular; the cut outs 13 of Fig. 4 are modified oblong; and the cut outs 16 of Fig. 5 are square. Other shapes of recesses may be made if desired. The principal purpose of the invention is to provide a more efficient clothespin which will not slip from the line either with or without goods being held thereby, either through gradual slipping or through whipping of the goods by wind.

The modification shown in Fig. 5 includes essentially square cut outs 16 having a greater width than height; the modification shown in Fig. 6 shows the cut outs 15 similarly square, or rectangular, but having a height greater than their width; in Fig. 7 the cut outs 12 are essentially circular in outline except for the top cut out which is a modified circle as shown; the modification illustrated in Figs. 8 and 9 shows diagonally positioned cut outs 17, having an essentially round or circular cross-section. This construction has an effective holding efficiency by virtue of the slanted grooves being jammed into the material held.

Having now described my invention, that which I claim as new, and desire to protect by Letters Patent, is:

A clothes pin having a body, a split therein, and a series of inclined grooves formed in each of the legs resulting from said split, each of the grooves being of a size to receive a clothes line and adapted to give said split greater holding power to any object placed over the clothes line in the split.

In testimony whereof I affix my signature.

GEORGE H. JENTZEN. 100
